UNITED STATES PATENT OFFICE.

WILLIAM R. PATTERSON, OF CHICAGO, ILLINOIS, ASSIGNOR TO THE WESTERN ELECTRIC MANUFACTURING COMPANY, OF SAME PLACE.

MERCURY TERMINAL FOR TELEGRAPH-CABLES.

SPECIFICATION forming part of Letters Patent No. 245,972, dated August 23, 1881.

Application filed April 1, 1881. (No model.)

To all whom it may concern:

Be it known that I, WILLIAM R. PATTERSON, of Chicago, Illinois, have discovered certain new and useful Improvements in Mercury 5 Terminals for Telegraph-Cables, of which the following is a full, clear, concise, and exact description.

In the class of cables to which my invention relates the conductors consist of wires severally wound with some fibrous material and bunched and bound together by a strong serving. The core of conductors thus prepared is drawn within a metallic pipe. Some insulating substance, either solid, liquid, or gaseous, 15 is introduced into the pipe, which fills the pores of the fibrous covering. When the insulating substance is a solid, like paraffine-wax, the fibrous covering of the several conductors may be omitted.

20 I will designate the pipe and cable of conductors properly laid as the "cable," and will speak of the cable of insulated conductors as the "core."

In the drawings, Figure 1 is an elevation of my 25 terminal. Fig. 2 is a detail of a portion thereof. Fig. 3 represents a vertical section of an oil-cable and a modified form of terminal. Fig. 4 is the form of binding-post which I find most convenient.

30 Like letters indicate like parts.

In Fig. 1 two conductors, *a*, are shown bound together by serving *b*. The metallic pipe *c* is bent so as to connect with the U-shaped pipe *d* of the terminal. The core ordinarily approximately fills the pipe *c*, and the pipe *d* is usually 35 somewhat larger than pipe *c*, in order that there may be room to splice the several conductors to their corresponding gutta-percha-covered or otherwise insulated wires *e*. Mercury *f* is introduced into the pipe, as shown, and rises and falls in response to the pressure upon the gas or dry air within the pipe. The wires *e* are 40 covered with some impervious insulating material, and extend from where they are spliced with the conductors *a* through the mercury in pipe *d* and project through the rubber cap *g*, as shown. All the wires *e* may come through 45 a single opening in the cap, in which case paraffine-wax may be turned in at the opening 50 around the wires, so as to keep them in place.

The glass tube *h* serves as a vent for the air when the mercury is acted upon by the pressure upon the gas or other substance of the cable. The height of the mercury may always be ascertained by observing the indicator *i*, 55 which may be graduated to indicate different degrees of pressure. I have provided an automatic signaling device for giving notice when the pressure falls below a certain limit.

k is a wire insulated with gutta-percha, except at its extremities. The lower end is adjusted so that it will not touch the mercury; but when the pressure is reduced the mercury will rise so as to touch the lower end of the wire *k*. By connecting a signal-bell and battery in a ground-line connecting with the upper end of wire *k* the decrease of pressure beyond a fixed limit may thus be automatically indicated.

When oil is used in the cable an extra bend 70 may be made in the cable in the form of an inverted U, in order to keep the oil from coming into direct contact with the covering of the wires in the terminal.

The terminal shown in Fig. 3 is useful when 75 one or a small number of wires are brought out at some point along the section of the cable.

The pipe *l* contains the core of conductors *m*.

The bushing *n* and hollow pin *o* are similar to the bushing and metallic pin described in 80 my Patent No. 233,162, of October 12, 1880. The mercury in pipe *p* protects the bushing from moisture, while the bushing prevents the transmission of pressure from the cable to the branch, and in case of injury to the branch protects the cable. Since there is no pressure from the cable upon the mercury within pipe *p* the vent is not necessary.

The wire or wires *q* may be carried out in the manner indicated in Fig. 1. When two or three 90 conductors are brought out together I use, preferably, a rubber plug or plate, instead of the bushing, and screw into holes provided in the plate as many metallic pins *r* (see Fig. 4) as there are wires *s* to be brought out. The wire 95 *s* is preferably brought through the pin and its end bent, as shown at *v*, Fig. 4. The binding-post *t* is then screwed onto the pin, so as to press firmly against the bent end of the wire projecting through the pin.

My invention has special reference to telegraph-cables in which dry air or other gas, either circulating or under pressure, is used to protect the severally-insulated conductors of the core, though it may be applied to any pipe telegraph-cable. When oil is used the gutta-percha-covered wires of the terminal must be protected from the oil. This may be done by an extra bend in the cable, near the terminal, as before indicated, so that capillary attraction will not draw the oil up to the splice, or in the manner indicated in Fig. 3. The mercury will effectually prevent moisture from penetrating to the splice.

15 In case iron is used for the pipe of the terminal, it should be amalgamated on the inside, so as to come in more intimate contact with the mercury.

The glass tube which forms the indicator *i* is of great advantage when it is desired to maintain a substantially uniform pressure upon the gas or liquid of the cable.

The rise or fall of the mercury may be made to indicate the fact at the office by means of suitable circuits, or may be made to automatically establish the pressure by connecting a tank previously charged, or by causing the generation of carbonic-acid gas by allowing acid to run upon marble-dust in a chamber connected with the cable.

The form of the bend in the terminal pipe is not essential, provided sufficient vertical space

is allowed in the two legs for the mercury, and this depends upon the amount of pressure within the cable.

35 The upper end of the outer branch of the terminal for a small number of the wires (shown in Fig. 3) may project above the surface of the ground or be so arranged that the wire or wires thereof may be accessible. The pressure upon the fluid of the cable is not transmitted to the mercury of the latter style of terminal, and therefore the mercury is at the same level in both branches of the bent pipe, and the indicating and signaling apparatus of the terminal 40 shown in Fig. 1 cannot be used.

I claim—

1. The terminal consisting of a U-shaped pipe in combination with mercury, through which one or more conductors are run, substantially as and for the purpose specified. 50

2. The terminal consisting of U-shaped pipe and mercury in said pipe, in combination with a rubber plug, one or more electric conductors and hollow pins, one for each conductor, and binding-posts, one for each hollow pin, substantially as and for the purpose specified. 55

3. The terminal consisting of pipe *d*, wires *e*, and mercury *f*, in combination with a cable, substantially as and for the purpose specified. 60

WILLIAM R. PATTERSON.
